UNITED STATES PATENT OFFICE.

MOSES A. KELLER, OF BATAVIA, NEW YORK.

COMBINED COMPRESSOR AND TRIP MECHANISM FOR HARVESTERS.

SPECIFICATION forming part of Letters Patent No. 537,777, dated April 16, 1895.

Application filed October 30, 1894. Serial No. 527,447. (No model.)

To all whom it may concern:

Be it known that I, MOSES A. KELLER, a citizen of the United States, residing at Batavia, in the county of Genesee and State of New York, have invented a new and useful Improvement in a Combined Compressor and Trip Mechanism for Self-Binding Harvesters, of which the following is a specification.

My invention relates to improvements in a compressor and trip mechanism in which the compressor is wholly supported upon the needle shaft, while in the normal position, and free to vibrate the needle shaft, to unclutch the binding mechanism, and when the needle is set in motion the said compressor operates in conjunction with a stationary switch, whereby the compressor is sustained in its upright position until the needle begins to recede, when said switch will cause the compressor to drop below the binding table to allow the bound gavel to pass out of the binder and as the needle reaches its normal position, the compressor is lifted to its normal position, by reason of its being coupled to the needle and wholly supported by the needle shaft, and the needle; second, by forming or having the clutch arm rigidly secured on the needle shaft, and the cranked arm journaled on the said shaft, and made to catch under said trip arm, and the operating pitman connected to said arm, and the main gear on the knotter operating shaft, and a tension spring connecting the trip arm, and cranked arm together whereby when the compressor rocks the needle shaft will unclutch the trip arm against the resistance of the said spring and set in motion the binding mechanism. By this construction and arrangement, I dispense with the special trip shaft, the compressor shaft and spring compressor link, and the cam mechanism in the main gear on the knotter operating shaft. In all it will save from one dollar to two dollars in first cost over the regular trip mechanism in general use, and by its simplicity and few working joints will be less liable to get out of order and insure better work of the machine. I attain these objects by the mechanism illustrated in the accompanying drawings, in which—

Figure 1 is a right hand side elevation or gear side of the binding mechanism. Fig. 2 is a

rear side elevation also in the normal position. Fig. 3 is a left hand side elevation also in the normal position. Fig. 4 is a left hand side elevation of the compressor mechanism and needle as the same are in operation compressing a gavel. Fig. 5 is another left hand side view of the compressor mechanism as the same would appear when fully compressed home in the operation of binding a gavel. Fig. 6 is another left hand side view showing the position of the compressor and needle, while the bound gavel is being discharged from the binding table. Fig. 7 shows detail parts of the switch plate and Fig. 8 shows detail parts of the clutch mechanism. Fig. 9 is a top view of the operating gears, the compressor mechanism and frame, the latter partially in section. Fig. 10 is a right hand side view of the clutch mechanism and compressor with switch plate removed but shown in dotted lines. Fig. 11 is a left hand side view, of the compressing mechanism with the compressing link removed to show how the compressor is supported in its upright and normal position. Fig. 12 is a plan view of the needle shaft with its clutch operating arm and the operating crank arm, and Figs. 13, 14, 15, 16 and 17 are detail parts of the compressor mechanism.

Similar letters and figures of reference refer to similar parts throughout the drawings, in which—

A denotes the main frame of the binding mechanism, and A' the supplemental frame to which the operating gears are secured and which also supports the table B'.

Journalized in the upper arm of the frame A is the main knotter operating shaft 4, to which is secured the main knotter operating wheel B, the knotter operating segment wheel O and the gavel ejector arms T. Into the lower arm of the frame A is journalized the needle operating shaft F.

To the supplemental frame A' is journalized the packer cranked shaft U and the clutch shaft Y. The gear wheels V and H² are rigidly secured on their respective shafts, and the clutch driving disk E² is also rigidly affixed to the shaft Y. The clutch holding disk E², and the sprocket wheel B⁴ are in one piece and are journalized on the shaft between the gear H², and clutch driver E². An endless chain C connects the wheel B with the wheel B⁴, the

latter being the driver. On the end of the needle shaft F, is formed or secured the clutch trip arm G, which has a hook at its free end to engage the clutch dog 11 when in its normal position as shown in Figs. 1 and 2.

Journalized on the needle shaft between the frame A and the clutch trip is the needle operating pitman arm E. A bolt with a spring D² holds the clutch trip arm and the needle operating arm together in the manner as shown in Fig. 1, and by reference to the drawings Fig. 12 it will be seen that the arm E catches under the trip arm G and they are held together by the action or power of the spring D² as shown in Figs. 1 and 9. The arm E is connected by a pitman D to a crank pin 12, that is on the wheel B. See Figs. 1 and 2.

The needle H is rigidly secured on the shaft F and has a short crank arm L². See Fig. 11. Into this crank is secured a pin or stud R. The compressor I is provided with two long slots P. and Q. as shown in Fig. 11 and by these holes is supported on the needle shaft F and stud R, while in the normal position as shown in Figs. 1, 2, 3 and 11.

Formed at the heel of the compressor is a projecting arm 16, on which is a compression spring R, a coupling link J and provided with a hole to receive the arm 16, and by a hole 20 is journalized on the stud R. in the manner as shown in Fig. 9, and several others, and the spring K is thus between the end of the coupling link and heel of the compressor, as clearly shown in Figs. 9 and 10. The end of said link is bent at right angles to the body of the link, as shown in Figs. 9 and 13, and on this end is journalized a roller L.

There is a switch plate M secured to the lower arm of the frame A. as shown in Figs. 1, 2, 3, 4, 5, 6 and 9. On the face of this plate is journalized a small angular switch N on a pin or stud 9, and is also provided with a pin 10, which enters the slot 3 in the plate, and projects through said slot and is engaged by a spring Z, see Figs. 7 and 9, and by this spring is held yieldingly in its normal position. There is also formed on the face of the plate M a projection or foot S and a projecting flange 2.

On Fig. 8 is given a plan of the construction of the clutch mechanism. As will be seen the clutch dog 11 is journalized to the face of the disk G² and a spring F² holds the roller 13 of the dog 11 in contact with the catches 14, that are formed on the inside of the flange of the driving disk E², as seen in dotted lines, but when the clutch dog is arrested and held by the trip arm G. the dog 11 will be in the position shown in Fig. 1 and the binding mechanism will then be out of gear and the dog 11 out of contact with the driving disk E².

Having thus given the general construction of the improved mechanism its operation as a whole is as follows: The grain as it accumulates on the table B' is caught by the usual packer W and packed between the table and breast plate of the knotter against the com-

pressor I, until the pressure of the grain against the compressor will cause the compressor to yield. Provision for this yielding is made in the switch plate M. When the compressor is in its normal position the roller L. with respect to the switch N. is in the position as shown in Fig. 3 and is held in this position by the force of the spring D² that is on the trip arm G; but when the compressor has yielded under the pressure of the grain to the position shown in dotted lines 7 Fig. 3 it has vibrated the needle to the point indicated by the dotted lines 8, Fig. 3, and consequently has vibrated the needle shaft F and trip arm G against the resistance of the spring D², for the reason that the arm E was held rigid by the pitman D, but this action of the yielding of the compressor has lifted the trip lever out of contact with the clutch dog 11 as shown in Fig. 10, and the roller L. of the compressor now rests on the vibrating switch N. as seen in Fig. 10 or in dotted lines Fig. 3. The lifting of the trip lever G. from the dog 11 has now set in operation the main wheel B through the chain C in the manner before described; and the pitman now lifts the arm E and draws it against the trip arm G to the full stroke of the crank pin 12, and as seen in dotted lines 15 Fig. 1; and by this operation the needle H is also brought up which divided the grain and compressed it against the compressor and this pressure holds the roller L. down on the switch N which will cause the switch to assume the position as shown in Fig. 4, and thereby close the open space 21, to allow the roller to pass over unto the foot S. without allowing the compressor to lower, and when the needle has been carried home to the knotter the pin R which actuates the compressor has now placed the compressor, the link J and roller L in the position shown in Fig. 5 and the spring Z has returned the switch N. to its normal position, as shown in Figs. 5, and 7, and thus opened the space 21. Now as the needle H begins to recede the pin R will push back the link J until the roller L passes off the foot S and drop through the opened space 21, and thus allow the compressor I to fall below the table B F, as seen in Fig. 6 and thus allow the ejector arm T to remove the bound gavel 5; and as the needle continues to recede, the pin R will again assume the position in the slot Q as shown in Fig. 11 and lift the compressor to its normal position. During this operation the roller L will again come in collision with the switch N in the manner shown in Fig. 15, and when the roller has reached its normal position shown in dotted lines 22, same figure, the spring Z will again restore the switch to its normal position and prevent the compressor to drop too far under pressure of the grain.

While the flange 2 prevents the compressor to fly up out of its proper position, simultaneously with this movement of the compressor and needle, the trip arm G will catch the clutch dog 11 and draw it out of engagement with the disk E², and thereby

stop the sprocket wheel B⁴ and consequently the wheel B, and all the binding mechanism.

I claim—

1. In a combined compressor and trip mechanism for binders the combination substantially as hereinbefore described, of the compressor journaled upon the needle shaft and provided with a slot around said shaft, and having a similar slot about a stud or pin that is secured in the heel extension of the needle or its equivalent, whereby the compressor is wholly supported upon the needle shaft while in its normal position, a switch secured to the lower arm of the binder frame next the binding needle, a supplemental compressor link journaled on the same pin of the heel extension of the needle, as the compressor, said link having a suitable hole to receive a short arm that is formed on the compressor and a supplemental compressor spring interposed between the rear end of said compressor link and heel of the needle, a projection or roller on said link to operate in conjunction with the switch, to sustain the compressor during the binding operation and at the conclusion of the binding operation cause the compressor to drop below the binding table to allow the bound gavel to pass out, and as the needle continues to recede allow the compressor to return to its normal position, as the needle comes to rest.

2. In a combined compressor and trip mechanism, the combination substantially as hereinbefore described, of the compressor, a binding needle and its shaft, a trip arm secured or formed on one end of said shaft and the needle at the other end said trip arm adapted to operate in conjunction with the clutch mechanism of the binder, a cranked arm journaled on the needle shaft next the trip arm, and connected by a pitman with the main binder operating wheel that is on the main knotter operating shaft, a tension spring connecting the trip arm and cranked arm, to cause the former to engage the clutch dog, the compressor journaled on the needle shaft next the needle by slots a pin or stud on the heel extension of the needle against which the compressor rests, when in its normal position, a supplemental compressor link journaled on the same pin of the heel extension and connected with the compressor and a spring interposed between said link and the heel of the compressor, and a switch to operate in conjunction with the said compressor link to sustain the compressor in the vertical position during the binding operation only, the said compressor being wholly supported on the needle shaft during the formation of a gavel and the pressure of the grain against the compressor causing the needle shaft to vibrate, and lift the clutch arm from the clutch dog against the resistance of the tension spring, and set the binder in motion.

3. In a combined compressor and trip mechanism, for binders, the combination with the vibrating binding needle and its shaft of a

compressor journaled on the needle shaft, and connected with the needle, a supplemental link journaled on the needle at a point distant from the needle shaft, and connected with the compressor, a spring interposed between a foot formed on said link, and the heel of the compressor to allow the compressor to yield, a switch adapted to operate in conjunction with the compressor, and control the same during the tying operation, a trip arm rigid on the needle shaft operating in conjunction with the clutch of the binding mechanism, and a tension spring connecting the trip arm with the pointed cranked arm of the needle shaft, the compressor being adapted to rock the needle shaft and cause the trip arm to release the clutch mechanism of the binder, all substantially as shown and described and for the purpose set forth.

4. In a combined compressor and trip mechanism for binders, the combination with the needle, its shaft, of a clutch trip arm rigid on the needle shaft to engage the clutch mechanism of the binder, the needle operating arm journaled on the needle shaft, a tension spring and bolt connecting said operating arm with the clutch trip arm, the compressor mounted on the needle shaft by slotted joint adapted to move on said shaft transversely to the longitudinal axis of the shaft, and wholly supported on the shaft while in the normal position; the actuating link of the compressor connected to the needle shaft to be operated thereby and connected to the compressor by sliding joint and a compressing spring, whereby the compressor can yield independently of the actuating link; the intermediate mechanism connecting the compressor actuating link, with the angular vibrating switch and stationary support, the whole being constructed for operation, substantially as shown and described.

5. In a combined compressor and trip mechanism for binders, the combination with the needle and its shaft, of the compressor mounted on the shaft by slotted joint adapted to move transversely on the shaft in its operative movement, and wholly supported on the shaft while in the normal position, to rock the needle shaft to clutch the binder operating gear, and the actuating mechanism of the compressor connected with the needle shaft, and operating in conjunction with a vibrating switch and stationary support, substantially as shown and described.

6. The combination with the needle and its shaft, of the clutch trip arm rigid on the needle shaft, the needle operating arm journaled on the needle shaft, and yielding connected to the trip arm; the compressor mounted on the needle shaft by slotted joint, and wholly supported on the shaft while in the normal position, to rock the needle shaft to clutch the binder operating gears, the compressor actuating mechanism connected to the needle shaft, and operating in conjunction with a stationary support; and vibrating angular switch

to carry the compressor in its operative movement in compressing the gavel and allow it to fall at the conclusion of the binding operation, and means to restore the compressor to 5 its normal position by the return movement of the needle shaft, all in the manner substantially as shown and described.

7. In combination with the needle its shaft and the clutch mechanism of the binder of the 10 compressor I loosely mounted on the needle shaft F by the slot P, and coupled to a pin R on needle by the slot Q so as to support the compressor when in the normal position, the supplemental coupling link J journaled on the 15 pin R, and loosely connected with the projecting arm 16 of the compressor, and a spring

K interposed between the heel of the compressor and rear end of the link J said link being adapted to draw the compressor up against the grain against the resistance of the 20 spring K, the roller L journaled on the link J and adapted to operate in conjunction with the vibrating cam switch N of the stationary switch plate M, and the stationary cam S, whereby the compressor I is controlled during 25 the binding operation, in the manner substantially as shown and described.

M. A. KELLER.
